UNITED STATES PATENT OFFICE.

GEORGE E. GREENLEAF, OF PLAINFIELD, HAROLD L. BLOOD, OF NORTH PLAINFIELD, AND ROSWELL H. RAUSCH, OF PLAINFIELD, NEW JERSEY, ASSIGNEES TO NILESBEMENT-POND COMPANY, OF NEW YORK, N. Y., A CORPORATION OF NEW JERSEY.

TOOL-OPERATING MECHANISM.

Application filed June 7, 1923. Serial No. 643,945.

This invention relates to planers and like machines and particularly to mechanism for operating the tools and tool supports thereof. Such machines ordinarily comprise a work table and one or a pair of uprights adjacent the table. A cross rail is mounted on the uprights and tool heads may be supported on the cross rail and on the uprights beneath the rail. The first said heads are ordinarily termed the "rail heads" and the second said heads are ordinarily termed the "side heads." Specifically, our present invention relates to mechanism for elevating and clamping the rail on the said upright or uprights and for feeding and traversing the tool heads. The primary object of the invention is to provide an improved mechanism for performing these functions.

It is an object of the invention to provide a planer with means for intermittently feeding the tools in synchronism with the reciprocation of the work table, and a motor for traversing the tools continuously, for moving the cross rail on the uprights and for clamping the rail to the uprights, the motor preferably being mounted on the cross rail.

It will be understood that while the said traversing, elevating and clamping functions may be most conveniently performed from the motor, it may in some instances be desirable to perform only certain of such functions therefrom. Accordingly, another object of our invention is to combine the use of a motor with a planer or like machine and its tool feeding mechanism, in the manner above stated for performing only certain of said functions as may be desired.

With the above and other objects in view, our invention consists in the features of construction and operation set forth in the following specification and illustrated in the accompanying drawings. In such drawings annexed hereto and forming a part of this specification, we have shown one form of our invention embodied in a planer but it will be understood that the invention can be otherwise embodied and that the drawings are not to be construed as defining or limiting the scope of the invention, the claims appended to this specification being relied upon for that purpose.

Referring to the figures of the drawings: Figure 1 is a side elevation of a planer embodying our invention.

Fig. 2 is a front elevation thereof. 55

Fig. 3 is an enlarged fragmentary plan view partially in section of one end of the cross rail.

Fig. 4 is an end elevation thereof.

Fig. 5 is a detail front view of certain 60 clutch mechanism shown in Fig. 4.

Fig. 6 is a fragmentary plan view of the cross rail shown in Fig. 2.

Fig. 7 is a rear elevation thereof.

Fig. 8 is a cross sectional view thereof 65 taken on line 8—8 of Fig. 7.

Fig. 9 is a cross sectional view taken on line 9—9 of Fig. 7.

Referring more specifically to the drawings by reference characters, 1 indicates the bed of a planer having a work table 2 slidably mounted thereon and a pair of uprights 3 respectively at opposite sides of the table. A cross rail 4 is mounted to slide vertically on the uprights and is adapted to slidably support a pair of tool head saddles 5 and 6 thereon. A side head saddle 7 is supported on one upright beneath the cross rail. The table 2 is adapted to be reciprocated from a motor 8 and such reciprocation is automatically controlled by a pilot switch 9 operated by table dogs 10 and 11. This mechanism and its operation are fully described in Patent No. 1,299,192. The movements of the table may be controlled manually by 85 means of a pendent switch 12 which is described in detail in Reissue Patent No. 14,540 dated October 22, 1918.

Two threaded shafts or screws 13 are provided on the cross rail for respectively 90 moving the tool saddles 5 and 6 therealong and a splined shaft 13^a is provided for moving the tools vertically in the usual manner. A pinion 14 is loosely mounted on the forward end of each screw shaft and a ratchet pinion 15 is slidably splined thereon adjacent each pinion 14. The pinions 14 and 15 are provided with cooperating clutch teeth on their adjacent faces whereby the inner splined portion of the pinion 15 may be 100 engaged with the pinion 14. Operating handles 15^a are provided for shifting the

pinions 15. Two large gears 16 and 17 on a shaft 18 parallel with the screw shafts are respectively adapted to operate the pinions 14 and 15. The gear 16 is in mesh with the pinions 14, and the pinions 15 are adapted to be slid into meshing engagement with the gear 17. The gear 16 is adapted to be continuously rotated in either direction for traversing the tool supports and the gear 17 is adapted to be intermittently rotated for feeding the tool supports, all of which mechanism is hereinafter more specifically described.

A rack bar 19 is reciprocated vertically from a crank mechanism 20 oscillated through a definite angle at each table reciprocation in the usual manner. The upper portion of the rack meshes with a gear 21 keyed to the shaft 18, the gear 17 being keyed to the other end of this shaft. It will therefore be seen that the gear 17 is oscillated through a definite angle at each table reciprocation, the amount of such oscillation being adjustable by means of the adjusting screw in the crank mechanism 20. The tools and tool supports may therefore be fed intermittently at each table reciprocation by sliding the pinions 15 into mesh with the gear 17.

The side head 7 may be fed along its upright in like manner. A screw 22 journaled in the upright threadingly engages the side head 7 and is operatively connected to a horizontal shaft 23 by means of bevel gears 24. A ratchet pinion 25 on the shaft 23 is in mesh with a gear 26 on a parallel shaft 27. The shaft 27 is intermittently oscillated from the rack bar 19 which has teeth 28 meshing with a gear 29 on the shaft 27. A clutch 30 is adapted to connect the pinion 25 to its shaft 23. The side head may therefore be fed from the rack bar upon engaging the clutch 30 with the pinion 25.

An electric motor 31 is mounted on a rearwardly extending bracket on the cross rail and, as illustrated in the drawings, this motor is adapted to traverse the tool supports, to move the cross rail on the uprights and to clamp the cross rail to the uprights. The mechanism cooperating with the motor for performing these functions will now be described.

The gear 16 is loose on the shaft 18 and a worm 32 on the motor shaft directly engages this gear. A controller 33 with a handle 34 thereon is provided on the cross rail for controlling the rotation of the motor in either direction. When it is desired to traverse the tools or tool supports, the pinions 15 are slid into clutching engagement with the pinions 14 on the screw shafts if it is desired to operate whereupon such screw shafts may be continuously rotated in either direction as desired.

The motor also drives a vertical shaft 35

through a pair of bevel gears 36. A spiral gear 37 is loosely mounted on the shaft 23 adjacent the clutch 30. A spiral gear 38 splined to the vertical shaft 35 is in mesh with the gear 37, the shaft 35 being movable vertically with the cross rail and slideable within the gear 38. By this arrangement, the clutch may be engaged with the gear 37 and the side head traversed on the upright in either direction from the motor.

The cross rail 4 is supported on the uprights by means of a pair of nuts 39 journaled in the rail and respectively threadedly engaging a pair of screws 40 non-rotatably mounted in the uprights. The nuts are provided with worm wheel teeth thereon engaged by worms 41 on a shaft 42 extending along the rail. A gear 43 loose on the front end of this shaft is in mesh with the before mentioned gear 16. A clutch 44 is provided for operatively connecting the gear 43 to the shaft 42. The gear 16 is driven from the motor 31 and, through the mechanism described, the nuts may therefore be driven from the motor in either direction to elevate or lower the cross rail.

Clamping mechanism for the cross rail is provided as follows: Pivoted to the rail adjacent each upright by means of bolts 45 is a clamping element 46. The short arm of each clamping element extends over a projecting portion of the adjacent upright and engages the bevelled ends of a clamping plate 47. This plate is loosely mounted within the clamping element by means of pins 48 and the engagement of the element with the bevelled ends of the plate assures an even clamping pressure on the uprights. A sliding wedge 49 is adapted to operate each clamping element to perform the clamping operation. The wedges are operated by rods 50 connected thereto, and threadedly engaged within a rotary sleeve 51. The sleeve is adapted to be rotated by a gear 52 splined thereto, the sleeve being freely slideable axially within the gear. Outward movement of one wedge in the unclamping operation is limited by a stop pin 53, and outward movement of the other wedge, beyond the unclamping position, is resisted by a spring 54, the spring being mounted on the wedge rod between a rib of the cross rail and a collar 55 pinned to the rod.

Extending along the cross rail above and parallel with the rail elevating shaft 42 is a shaft 56. A gear 57 on the inner end of this shaft is operatively connected to the gear 52 by means of two idler gears 58 and 59. A gear 60 loose on the front end of the shaft is in mesh with the gear 43. A clutch 61 is provided for operatively connecting the gear 60 to its shaft 56. An operative connection is therefore established from the motor 31 to the gear 52 whereby to perform the clamping operation.

The front ends of shafts 42 and 56 are supported in a bracket 62 bolted to the end of the cross rail. A forwardly extending arm 63 is provided thereon for pivotally supporting a clutch operating lever 64. This lever is connected to the clutches 44 and 61 respectively at opposite sides of the pivotal point of the lever. Such arrangement provides means for shifting the clutches and positively assures that when either clutch is in the engaged position, the other clutch will be in the disengaged position, thus preventing the simultaneous engagement of these clutches and possible damage to the machine.

The operation of the machine is as follows: To start the reciprocation of the work table, the operator grasps one of the arms 9^a and rotates the pilot switch 9. The motor 8 thereupon moves the table in one direction until one of the table dogs engages its arm 9^a and rotates the pilot switch in the opposite direction. Such operation reverses the motor which then drives the table in the opposite direction. The tool feeding rack bar 19 is reciprocated at each reciprocation of the table in the usual manner.

To perform feeding operations, the ratchet pinions 15 on the shafts it is desired to operate are meshed with the gear 17 and the screw at 20 is adjusted to give the rack feeding stroke desired. If the side head 7 is to be fed, the clutch 30 is engaged with the ratchet pinion 25. With the parts in these positions, it is obvious that the tools will be automatically fed the desired amount during each successive non-cutting interval in the operation of the machine, such operation being performed directly from the table reciprocating mechanism.

When it is desired to traverse the tools or tool saddles continuously by power, the pinions 14 and spiral gear 37 of the shafts it is desired to operate are clutched to their shafts respectively by means of the engagement of ratchet pinions 15 and clutch 30 therewith. After making such adjustments, the motor may be operated in either direction to traverse the tools and tool supports as desired. It will be understood that during this operation, the elevating and clamping clutches 44 and 61 are in the inoperative position illustrated in Fig. 5.

When it is desired to move the cross rail on the uprights, the ratchet gears 15 and clutch 30 are placed in the neutral position and the clutch 44 is engaged with its gear 43. The elevating nuts 39 may now be continuously rotated from the motor 31 in either direction to elevate or lower the cross rail on the uprights.

After adjusting the cross rail to the desired position, the same may be clamped to the uprights by means of the motor 31 as follows: The lever 64 is moved to disengage

the clutch 44 and engage the clutch 61. The motor 31 and gear 52 may now be rotated in a direction to draw the wedges inwardly and force the clamping elements 47 into clamping engagement with the uprights. As before stated, the threaded sleeve 51 is freely slidable axially in its bearings whereby both wedges are drawn inwardly with equal force and thereby assure an equal clamping action on both uprights. To unclamp the rail, the motor is rotated in the opposite direction whereby the rods 50 and wedges 49 are forced outwardly. The stop screw 53 limits the outward movement of one wedge and the spring 54 resists the outward movement of the other wedge beyond its unclamping position. These stop means assure the release of both clamping wedges in the unclamping operation.

What we claim is:

1. In a planer or the like, the combination of a base, a reciprocating work table mounted thereon, two uprights respectively at opposite sides of the table, a cross rail mounted to slide vertically on the uprights over the table, a tool support movably mounted on the rail, means for intermittently feeding the tool support synchronously with the table reciprocation, a motor, and mechanism operated by the motor for traversing the tool support continuously, for moving the rail on the uprights and for clamping the rail to the uprights.

2. In a planer or the like, the combination of a base, a reciprocating work table mounted thereon, two uprights respectively at opposite sides of the table, a cross rail mounted to slide vertically on the uprights over the table, a tool support movably mounted on the rail, a tool support on one upright beneath the rail, means for intermittently feeding the tool supports synchronously with the table reciprocation, a motor, and mechanism operated by the motor for traversing the tool supports continuously, for moving the rail on the uprights and for clamping the rail to the uprights.

3. In a planer or the like, the combination of a base, a work table mounted thereon, two uprights respectively at opposite sides of the table, a cross rail mounted to slide vertically on the uprights over the table, a tool support movably mounted on the rail, a motor on the rail, and mechanism operated by the motor for traversing the tool support continuously and for clamping the rail to the uprights.

4. In a planer or the like, the combination of a base, a reciprocating work table mounted thereon, means for reciprocating the table, two uprights respectively at opposite sides of the table, a cross rail mounted to slide vertically on the uprights over the table, pivoted clamping means on the rail for securing the rail to the uprights, a tool

- support movably mounted on the rail, means operated from the table reciprocating means for intermittently feeding the tool support synchronously with the table reciprocation, a motor on the rail, and mechanism operated by the motor for traversing the tool support continuously, for moving the rail on the uprights and for operating the clamping means.
10. 5. In a planer or the like, the combination of a base, a reciprocating work table mounted thereon, means for reciprocating the table, two uprights respectively at opposite sides of the table, a cross rail mounted to slide vertically on the uprights over the table, a tool support movably mounted on the rail, a screw operatively connected to the support, two coaxial gears on the rail rearwardly of the screw, means adapted to operatively connect either gear with the screw, mechanism for intermittently rotating one gear from the table reciprocating means, a motor on the rail operatively connected with the other gear, the said one gear being adapted to intermittently feed the tool support synchronously with the table reciprocation and the said other gear being adapted to traverse the tool support continuously, and mechanism operated from the motor operated gear for moving the rail on the uprights.
6. In a planer or the like, the combination of a base, a reciprocating work table mounted thereon, means for reciprocating the table, two uprights respectively at opposite sides of the table, a cross rail mounted to slide vertically on the uprights over the table, a tool support movably mounted on the rail, a screw operatively connected to the support, two coaxial gears on the rail rearwardly of the screw, means adapted to operatively connect either gear with the screw, mechanism for intermittently rotating one gear from the table reciprocating means, a motor on the rail operatively connected with the other gear, the said one gear being adapted to intermittently feed the tool support synchronously with the table reciprocation and the said other gear being adapted to traverse the tool support continuously, and mechanism operated from the motor oper-
- ated gear for moving the rail on the uprights and for clamping the rail to the uprights.
7. In a planer or the like, the combination of a base, a reciprocating work table mounted thereon, means for reciprocating the table, an upright on the base at one side of the table, a cross rail mounted to slide vertically on the upright and extending horizontally over the table, a tool support movably mounted on the rail, means for intermittently feeding the tool support synchronously with the table reciprocation, a motor, and mechanism operated by the motor for traversing the tool support continuously, for moving the rail on the upright and for clamping the rail to the upright.
8. In a planer or the like, the combination of a base, a reciprocating work table mounted thereon, means for reciprocating the table, an upright on the base at one side of the table, a cross rail mounted to slide vertically on the upright and extending horizontally over the table, a tool support movably mounted on the rail, a motor on the rail, and mechanism operated by the motor for traversing the tool support continuously and for clamping the rail to the upright.
9. In a machine of the class described, the combination of a base, a work table thereon, two uprights respectively at opposite sides of the table, a cross rail mounted to slide vertically on the uprights over the table, screw threaded means adjacent the uprights for moving the rail thereon, clamping means for securing the rail to the uprights, a shaft extending along the rail and operatively connected to the screw threaded means, a shaft extending along the rail and operatively connected to the clamping means, a motor on the rail, and clutch means for engaging either shaft with the motor whereby to move the rail on the uprights and to clamp the rail thereto.

In testimony whereof, we hereto affix our signatures.

GEORGE E. GREENLEAF.
